COMBINATION SKILLET

Vergil Cunningham, Chicago, Ill.; Darrow D. Dorr, executor of said Vergil Cunningham, deceased, assignor to Durward D. Dorr, Chicago, Ill.

Application May 13, 1953, Serial No. 24,988

Term of patent 14 years

(Cl. D44—1)

To all whom it may concern:

Be it known that I, Vergil Cunningham, a citizen of the United States of America, residing at Chicago, in the county of Cook and State of Illinois, have invented a new, original, and ornamental Design for a Combination Skillet, of which the following is a specification, reference being had to the accompanying drawing, forming a part hereof.

In the drawing,

The aspect of my invention pertaining to the design of a single skillet is disclosed and claimed in my co-pending divisional application entitled Skillet, Serial No. D. 30,628, filed May 24, 1954.

I claim:

The ornamental design for a combination skillet, substantially as shown.
